F. O'BRIEN,

COUNTERBALANCE FOR CRANK SHAFTS AND METHOD OF APPLYING THE SAME
APPLICATION FILED JUNE 4, 1917.

1,261,053.

Patented Apr. 2, 1918.

By *Frank O'Brien*

Attorney

UNITED STATES PATENT OFFICE.

FRANK O'BRIEN, OF FLINT, MICHIGAN.

COUNTERBALANCE FOR CRANK-SHAFTS AND METHOD OF APPLYING THE SAME.

1,261,053.

Specification of Letters Patent.

Patented Apr. 2, 1918.

Application filed June 4, 1917. Serial No. 172,662.

To all whom it may concern:

Be it known that I, FRANK O'BRIEN, a citizen of the United States of America, residing at Flint, in the county of Genesee 5 and State of Michigan, have invented certain new and useful Improvements in Counterbalances for Crank-Shafts and Methods of Applying the Same, of which the following is a specification, reference 10 being had therein to the accompanying drawings.

The invention relates to the art of counterbalancing crank-shafts, and it is the object of the invention to provide means 15 readily attachable to the crank-shaft for forming a variable counterweight, and which is securely held from displacement. More specifically the invention comprises a laminated counterbalance, the laminæ being 20 attachable to the crank-shaft in varying number to secure an exact balance. The invention further comprises various specific features of construction as hereinafter set forth.

25 In the drawings:

Figure 1 is a sectional elevation of a portion of a crank-shaft showing the counterbalance applied thereto;

Fig. 2 is an end elevation thereof;

30 Fig. 3 is a section on line 3—3 Fig. 2;

Fig. 4 is a side elevation of one of the laminæ;

Figs. 5 and 6 are respectively a plan and a cross-section thereof;

35 Figs. 7 and 8 are views similar to Figs. 4 and 6 showing the locking laminæ.

A is the crank-shaft, B one of the throws thereof and C a lug projecting oppositely from said throw and to which the counterbalance is applied. This lug C is preferably of a dove-tail or wedge-shape cross-section and is formed with a slit D in the plane of rotation, preferably centrally thereof. E are the laminæ, preferably cut from sheet-metal and fashioned to the desired contour, including a wedge-shaped recess F for fitting over the wedge-shaped cross-section of the lug C. G is a lamina similar in external contour to the lamina E but provided with 45 a portion H extending into the recess F and engageable with the slit D in the lug C. The laminæ E and G are formed with a series of registering apertures I for securing the same to each other by pins or rivets.

50 In the operation of counterbalancing a crank-shaft the laminæ E are engaged with

the lug C by slipping endwise over the same while the lamina G is moved in the plane of rotation into engagement with the slit D. When thus engaged all of the laminæ are 60 secured to each other by bolts or rivets J passing through the registering apertures I. Thus the dove-tail engagement between the laminæ E and the lug C will hold the same from disengagement in the plane of rotation 65 and will resist centrifugal action, while the engagement of the lamina G with the slit D will lock the whole series from lateral movement out of engagement with the lug. I preferably form the angling sides K of the 70 recess F of obliquely-turned portions, thereby permitting of a slight expansion when forced upon the lug C and constituting a resilient engagement for preventing rattling. If desired, the opposite ends of the series 75 may be bounded by plates L and L' of greater strength and thickness, which are secured by the same bolts or rivets J.

A counterbalance of the construction described may be readily applied, and by the 80 removal or addition of one or more of the laminæ the weight may be adjusted to the desired balance.

What I claim as my invention is:

1. The method of counterbalancing crank-shafts, comprising the forming of a weight of laminæ having individual and interlocking engagement with the crank and adjusting the balance by the addition or removal of one or more of the laminæ, and locking 85 the adjusted series to each other.

2. A counterbalance for crank-shafts, comprising a plurality of laminæ individually engageable with and removable from the crank-shaft, and means for locking the 95 series.

3. A counterbalance for crank-shafts, comprising a plurality of duplicate sheet-metal blanks individually engageable with the crank-shaft by a movement transverse to the 100 plane of rotation, the engagement being such as to lock said blanks from movement relative to said shaft in the plane of rotation.

4. A counterweight for crank-shafts, comprising a plurality of laminæ individually 105 engageable with the crank-shaft by a movement transverse to the plane of rotation and interlocking with said shaft to prevent relative movement in the plane of rotation, and means for locking said laminæ from transverse movement relative to each other and said shaft.

5. A counterbalance for crank-shafts, comprising a plurality of laminae engageable with said crank-shaft by a movement transverse to the plane of rotation and interlocking to be immovable in the plane of rotation, a lamina engageable with said crank in the plane of rotation and locked from movement transverse to said plane, and means for securing all of said laminae together, whereby 5 the entire series is locked from relative movement to said shaft in any direction.
6. The combination with a crank-shaft, of a dove-tail lug projecting from said crank opposite to one of the throws thereof, a series 10 of laminae recessed to be engageable with said dove-tail lug by a movement transverse to the plane of rotation, and means for locking said series from transverse movement.
7. A counterbalance for crank-shafts, comprising a lug integral with the shaft, pro- 15

jecting oppositely from a throw thereof and of a dove-tail cross-section in the plane of rotation, a series of laminae recessed to be engageable with said lug by a movement transverse to the plane of rotation, an edge 25 of each lamina being resiliently yieldable to form a clamping engagement with said lug, and means for locking the series from transverse movement.

8. A counterbalance for crank-shafts, comprising a series of laminae formed from sheet-metal stampings, provided with a locking recess engageable with a dove-tail lug on the crank when moved transverse to the plane of rotation, the edge portions of said 30 laminae adjacent to said lug being turned to form a yieldable resilient engagement therewith.

In testimony whereof I affix my signature.
FRANK O'BRIEN.
